UNITED STATES PATENT OFFICE.

NICHOLAS SPEICHER, OF ST. PAUL, MINNESOTA.

PERMUTATION-PADLOCK.

SPECIFICATION forming part of Letters Patent No. 352,373, dated November 9, 1886.

Application filed April 1, 1886. Serial No. 197,441. (Model.)

To all whom it may concern:

Be it known that I, NICHOLAS SPEICHER, a citizen of the United States, residing at St. Paul, in the county of Ramsey and State of Minnesota, have invented an Improved Combination or Permutation Padlock; and I do hereby declare that the following is a full and exact description of the same, reference being had to the accompanying drawings, making part of this specification.

My invention belongs to the class of padlocks; and it consists in the special features of improvement hereinafter set forth.

The principal or essential parts of the padlock are a locking-shackle of hook form, a cylindrical inner shell, in which the shackle slides, a series of circular plate or disk tumblers situated and revolving within the said shell for locking and unlocking the shackle, and a cylindrical outer shell surrounding the inner shell, and serving as the instrument by which the operator actuates the tumblers to lock and unlock the shackle; also, a set of ring-washers are located between the several tumblers to keep the same separate from one another and in the exact positions required; and another washer or block is preferably used and located in the outer shell between the outermost tumbler and the outer closed end or head of the said shell, for holding all the tumblers in place, and for tightly closing the aperture in the said head of the shell against the admission of dust or dampness into the interior of the padlock.

In the accompanying drawings, Figure 1 represents a side view of the shackle; Fig. 2, a side view of said shackle, taken in a direction at right angles to the view in Fig. 1; Fig. 3, a side view of the inner shell; Fig. 4, an open end view of the same; Fig. 5, a similar view of the inner shell with the shackle inserted therein; Fig. 6, a side view of the outer shell; Fig. 7, an inner end view of the same; Fig. 8, a side view of one of the disk-tumblers; Fig. 9, an opposite side view of the same; Fig. 10, a side view of one of the ring-washers used between the tumblers; Fig. 11, an edge view of all the tumblers and ring-washers placed together as when located in the inner shell; Fig. 12, a side view of the outer packing-washer located in the

outer shell; Fig. 13, a side view of the entire padlock, showing the shackle locked; Fig. 14, a side view thereof, with the shackle unlocked and drawn out; Fig. 15, a central axial section of the whole padlock, the shackle being locked; Fig. 16, an end view of the inner shell, showing one of the tumblers therein in two positions, locked and unlocked; Fig. 17, a side view of the inner shell, showing a modified form of the same; Fig. 18, an axial section of the same and of the outer shell around it, showing another modification of the inner shell.

In the drawings, A represents the shackle; B, the inner shell; C, the outer shell; D E F G, a series of four disk shape tumblers located in the inner shell; H H H, the ring-washers between the tumblers, and I the outer packing washer or block between the tumblers and the head of the outer shell.

The shackle A has a straight body or shaft, a, and a hook, b, which enters the staple of the article to be locked, and c the extremity of the hook turned to a position parallel with the shaft a. The shaft a extends through the centers of the two shells and of the tumblers and washers, and slides inward and outward therein to lock or unlock. The aperture through the head d of the inner shell, B, may be round, so that the shackle may turn therein when it is unlocked and partly drawn out; but when the shackle is pushed into the shell as far as it will go, then not only does the end c of the hook of the shackle enter an aperture through a lateral extension or flange, e, of the shell, but there is a pin or projection, f, on the shaft of the shackle to enter a notch, g, in the head d of the shell next to its central shaft aperture or eye. Thus the shackle, when locked, is held against turning to any appreciable extent in the shell. The shackle enters the hole of the flange e and its pin enters the notch g simultaneously, so that no care is required in pushing the shackle into place for locking. The inner surface of the end c of the hook of the shackle is flattened or cut away to a plane surface, so as to fit closely over an extension, h, of the flange e, extending parallel with the shaft of the shackle outside of the two shells. This extension receives a coupling pin or screw, i, projecting inward through the same and into an annular groove, j, in the pe-

riphery of the outer shell, C, which fits over the inner shell for the purpose of keeping the two shells together and to prevent getting access to the interior work of the padlock. The 5 flattened end of the shackle, constructed and arranged as shown, and as above set forth, covers, conceals, and shields the coupling pin or screw *i* when the shackle is locked, but allows access to it when the shackle is un-
locked and drawn out. A rim, *k*, around the head of the inner shell, extends outward flush with the external periphery of the outer shell, which fits close up to the rim, as shown. In Fig. 17 I have shown a modified construction 15 of the inner shell, in having an extension over the outer shell parallel with its axis entirely around the said shell, instead of the mere extension *h*, shown in other figures of the drawings. Such a peripheral extension entirely 20 covers and conceals the coupling-groove of the outer shell.

The main part of the shaft *a* of the shackle is not round or cylindrical, but has some other form, which, fitting accurately in an aperture of the same outline form in each tumbler, 25 will prevent the tumblers from turning thereon. The form shown in the drawings is a partial cylinder with a flattened side, *l*, formed by cutting away considerably less than one-half 30 of the shaft, as shown, and the tumblers all have a form to accurately fit the shaft. This is a good form, and is easily made. Then, of course, in order to lock the shackle by those tumblers, they or some one of them must be 35 turned out of position, which will not allow the shackle to register with the same and slide therein. For this purpose the shaft *a* of the shackle is cut away or notched at *m n o p*, leaving a central rounded axis of the shaft of sufficient 40 strength, each notch being of sufficient width to receive its tumbler, and the several notches being separated by strong webs or partitions *q q q*, or portions of the shackle-shaft of the full size to fit in the tumblers. The tum-
blers are separated by the ring-washers H H 45 H, which occupy positions around the several webs, so as to hold the several tumblers in the exact positions necessary to turn in their respective notches when the shackle is in locking 50 position.

The tumblers are preferably, if not essentially, made of different thicknesses, and their notches are also correspondingly of different widths, the inner one being thickest and the 55 others successively somewhat thinner to the outermost one. The purpose of having these different thicknesses is to prevent the tumblers from ever turning on the shackle-shaft when the said shaft is partly drawn out or pushed 60 in through the tumblers, and thus locking the shackle in the wrong position; and it is obvious that with this construction none of the tumblers can turn in any of the notches, except when the shackle is pushed completely into locking 65 position. On the other hand, the intermediate washers and the webs of the shackle-shaft are preferably made of uniform thickness, so

that only one thickness thereof is required to be made. The ring-washers are not whole, but are each separated at one point, in order 70 that they may be made elastic and spring outward into very shallow grooves *r r* in the interior periphery of the shell, as shown in Fig. 15; but this construction with grooves, though preferable, is not essential, and the inner periphery may be made even and smooth, as 75 shown in Fig. 18.

The several tumblers are turned for locking and unlocking the shackle by turning the outer shell, C, around the inner shell. A pin, *s*, projecting from the inner surface of the head of the shell, strikes a short pin or projection, *t*, on the outer surface of the outer tumbler, in a corresponding circle to turn that tumbler in either direction, and similarly a pin, *u*, on the inner surface of the outer tumbler, strikes a pin, *t*, on the outer surface of the next tumbler, to turn it in either direction, and successively a pin on the inner surface of each tumbler strikes a pin on the outer surface of the next inner tumbler to 90 turn the same. These pins are all in corresponding circles and at different angles or distances from the same initial point—as, for instance, the middle of the flat side of the aperture in each tumbler, according to the form 95 shown in the drawings—so that the several tumblers have to be turned to different angles to register with the shaft of the shackle. These angles or distances are arbitrarily fixed, whereby a great variety of permutations may 100 be produced, proper instructions being given the purchaser of each padlock as to what extent of turning movement is required for each tumbler. This is conveniently expressed by 105 numbers, the whole circumference being, for example, and as represented in the drawings, divided into sixty parts and properly numbered; and by reversing the sides of either tumbler a different number is or may be produced, as indicated in Figs. 8 and 9, whereupon 110 the tumbler shown is marked 56 on one side and 48 on the other. With such a construction and capability of reversion a padlock with four tumblers will give all the permutations or changes that may be desired. The 115 number of each may be indicated by stamping on the sides of the tumblers, as indicated in the said figures referred to, or given in printed directions accompanying each padlock.

In order that the innermost tumbler may be 120 reversed as well as the others, an annular groove, *v*, is formed in the bottom or inner surface of the head of the inner shell for the inner coupling-pin of that tumbler to run in.

An index-scale, *w*, is formed on the outer 125 periphery of the outer shell, C, showing the requisite number of divisions as sixty, (shown in the drawings,) and suitably numbered. A starting or zero mark, *x*, is also made on the adjacent rim of the inner shell, as a guide to 130 the movements of the outer shell in locking and unlocking.

With a construction such as thus far set forth the padlock may be locked and un-

locked, for example, as follows: To lock the shackle, after it has been pushed into place, or locking position, the zero-point on the index-scale is brought to the guide-mark or 5 pointer on the inner shell, and the outer shell is then turned one revolution either to the right or to the left. Now, for one example of unlocking, the tumblers being arranged therefore, the manipulation may be as follows: First, 10 turn the outer shell five revolutions to the left, finally bringing the zero-mark on the outer shell accurately opposite to the pointer-mark on the inner shell; second, turn the outer shell to the right until the division 36 is brought 15 opposite to the pointer-mark, and then continue to turn it in the same direction three revolutions farther, finally bringing the mark 36 exactly opposite to the pointer-mark; third, turn the outer shell to the left until the division 20 56 is brought to the pointer-mark, and two revolutions farther, finally bringing the mark 56 accurately to the pointer-mark; fourth, turn the outer shell to the right till the division 32 is brought to the pointer-mark, and 25 one revolution farther, finally bringing the mark to the pointer-mark. The shackle is then free, and can be drawn out.

Now, to illustrate a change in the permutation, Fig. 8 shows a tumbler marked 56. 30 This corresponds with the division marked 56, mentioned in the directions above given. Then suppose that particular tumbler to be reversed in the padlock, showing the number 48, as indicated in Fig. 9. With this change, instead of turning the outer shell to the division 35 56, as directed in the third step of the process, the division 48 is to be used. This will illustrate how the method of changing the combination is simple and easily effected. 40 The outer edge, *y*, of the outer shell may be milled, to roughen it and allow a firm hold of the shell while manipulating it. The shackle-shaft projects entirely through the shells of the padlock and considerably beyond the same, so 45 that sufficient sliding movement may be given thereto to attach it to and detach it from the staple of the article or thing locked. In order that the shaft may not be entirely drawn out of the shells, a stop is removably attached to 50 the projecting end of the bolt-shaft. This may conveniently be in the form of a ring, *J*, sprung into a hole in the end of the bolt.

In order to exclude moisture, dust, or corroding vapors from the interior of the padlock, 55 a packing washer or block, *I*, is or may be placed inside of the outer shell around the shaft of the shackle, which accurately fits an aperture in the washer, which is cylindrical on its outer periphery, accurately fitting the 60 cylindrical shackle-aperture in the body of the shell, and a shoulder, *z*, on the washer fits closely against the inner surface of the head of the shell to fulfill the purpose above specified. The interior surface of the head of the shell may be countersunk to receive this shoulder, as shown; but this is not essential.

I claim as my invention—

1. In a permutation padlock, the combination of an inner shell, a series of locking tumblers revolving within the shell, an outer shell 70 revolving around the inner shell for turning the tumblers, and a hook-shackle extending axially through the shells and tumblers, and sliding therein, for securing or releasing the article to be locked, substantially as herein 75 specified.

2. The combination of a shackle, *A*, having a notched shaft, *a*, inner shell, *B*, in which the shackle slides, revolving outer shell, *C*, surrounding the inner shell, and tumblers *D E F G*, located and turning in the inner shell, having apertures accurately fitting the general form of the shackle-shaft, and adapted, respectively, to turn in the notches of the shackle-shaft by the turning of the outer shell, for locking and unlocking the shackle, substantially as herein set forth.

3. The combination of the shackle *A*, having a series of tumbler-receiving notches, *m n o p*, of different widths, a series of locking tumblers, *D E F G*, all of different thickness, and respectively fitting the said notches, an inner shell, *B*, in which the shackle slides, and revolving outer shell, *C*, surrounding the inner shell, substantially as and for the purpose 95 herein specified.

4. The combination of the tumblers, the intermediate spring washer-rings, and the inner containing-shell slightly grooved in its inner periphery to retain the washer-rings, substantially as herein specified.

5. The combination of the shackle *A*, having a hook-extension, *e*, and a coupling pin, *f*, on its shaft, and the inner shell, *B*, having a perforated extension-flange, *e*, to receive the 105 said hook-extension, and a notch, *g*, in its head *d*, to receive the said coupling-pin, substantially as and for the purpose herein specified.

6. The combination of the outer shell, *C*, having an annular groove, *j*, in its outer periphery, the inner shell, *B*, having a flange-extension, *h*, projecting over the said coupling-groove of the outer shell, and provided with an inwardly-projecting coupling pin or screw, *i*, and the shackle *A*, having a hook-extension, 115 *e*, covering the said coupling screw or pin when the shackle is locked, for the purpose herein specified.

7. The combination of the outer shell, *C*, having a cylindrical aperture in its head, the 120 shackle *A*, extending through the same, and the packing washer or block *I*, fitting around the shackle-shaft, and turning in the aperture of the head of the shell, for the purpose herein specified.

8. The combination of the sliding shackle *A*, having tumbler-notches *m n o p* in its shaft, with intermediate webs, *q q q*, thereon, the inner shell, *B*, having a pointer-mark thereon, revolving tumblers *D E F G* within the shell 130 *B*, fitting the respective notches in the shackle-shaft, and having coupling pins *t u* on their faces, washers *H H H* between the respective tumblers for keeping the tumblers in position,

and outer shell, C, having a coupling-pin, s, to couple it with the outer tumbler, and an index-scale on its periphery adjacent to the pointer-mark on the inner shell for accurately determining the revolving movements of the said outer shell in locking and unlocking the shackle, substantially as and for the purpose herein specified.

In testimony whereof I have hereunto set my hand in presence of two subscribing witnesses.
